CLAIM

The ornamental design for a can grip device as shown and described.

DESCRIPTION

FIG. 1 is a perspective view illustrating a can grip device; FIG. 2 is front elevation view thereof; FIG. 3 is rear elevation view thereof; FIG. 4 is a left-side elevation view thereof; FIG. 5 is a right-side elevation view thereof; FIG. 6 is a top plan view thereof; FIG. 7 is a bottom-rear perspective view thereof; and, FIG. 8 is a perspective view thereof, shown in a user's hand with a can connected thereto. The broken lines appearing in the several views form no part of the claimed design. Unclaimed subject matter is shown in broken lines for the purpose of illustrating the environment in which the article embodying the design is used.
